UNITED STATES PATENT OFFICE.

SAMUEL CROCKER, OF OKLAHOMA, OKLAHOMA TERRITORY.

GAME APPARATUS.

SPECIFICATION forming part of Letters Patent No. 592,081, dated October 19, 1897.

Application filed March 16, 1897. Serial No. 627,807. (No model.)

To all whom it may concern:

Be it known that I, SAMUEL CROCKER, a citizen of the United States, residing at Oklahoma, in the county of Oklahoma and Territory of Oklahoma, have invented a new and useful Game, of which the following is a specification.

This invention relates to certain improvements in game apparatus, and more especially to such games as are played with cards in connection with a tally-board and scoring pins or pegs; and the object of the invention is to provide a game of this character of a simple, entertaining, and instructive nature adapted to be played by two or more persons.

The invention consists in certain novel features of the construction, combination, and arrangement of the apparatus employed in playing the improved game, all as will be hereinafter fully set forth.

The novel features of the invention will be carefully defined in the claim.

In order that my invention may be the better understood, I have shown in the accompanying drawings an apparatus embodying my improvements, in which drawings—

Figure 1 is a plan view of the tally-board employed for scoring the game, and Fig. 2 is a section taken transversely through the same on the line xx in Fig. 1. Fig. 3 is a view showing the pins or pegs employed in connection with the tally-board shown in Fig. 1. Fig. 4 is a view showing certain of the cards to be employed in playing the game.

As shown in the drawings, the tally-board is formed of a flat rectangular tablet 1, having legs 2, preferably formed of cork or similar soft substance, secured to its under side at its corners. The upper face of the tablet 1 is covered over with a sheet 3 of cardboard, celluloid, or other material cemented or otherwise secured upon the tablet and having printed upon its surface the various markings and directions to guide the persons in playing and scoring the game, as will be explained in detail hereinafter.

In the tablet 1 are formed two sets of apertures 4 and 4^a , one for each of the two players, the set 4 being arranged at the left-hand side of the tablet, as shown in Figs. 1 and 2, and the set 4^a being arranged at the right-

hand side of the tablet, each set comprising three columns of apertures extending longitudinally along the tablet. These apertures are adapted to receive pins or pegs 5, the forms of which are shown in Fig. 3, these pins or pegs 5 being employed for scoring the game, as will be hereinafter explained.

The cards 6 (shown in Fig. 4) employed in playing the game will be also hereinafter described.

The two outer columns of apertures in each set 4 and 4^a are formed into parallel series 7 and 8 at the upper end of the tablet, there being, as shown, twenty-five apertures in each series 7 and 8. The sheet 3 forming the face of the tally-board has printed on it rulings forming spaces 9 and 10, inclosing the respective series 7 and 8 of apertures, and in said spaces opposite the respective series of apertures are printed or otherwise formed corresponding series 11 and 12 of guide-numbers, each guide-number being arranged opposite to one of the apertures in the respective series 7 and 8.

Above each of the spaces 9 at each side of the tablet is printed the word "Silver," and said word, together with the guide-numbers 11 in said space, will be, by preference, printed in silver-bronze or ink of a distinctive color, while over each space 10 is printed the word "Gold," this word and the corresponding series of guide-numbers 12 being printed in gold-bronze or other distinctive color.

Each series 11 begins with the number "16," and its numbers increase in arithmetical progression by the successive addition of sixteen, so that the series reads "16, 32, 48," and so on down to "400." Each series 12 begins with the number "1" and also increases by the successive addition of one, so that it reads "1, 2, 3," and so on down to "25." By this arrangement it will be seen that the numbers opposite each other in the respective series 11 and 12 may be read together, being opposite each other—as, for example, "16 to 1," "32 to 2," "48 to 3," and so on down to "400 to 25," and it will thus be seen that each two opposite numbers in the series 11 and 12 are to each other in the relation of sixteen to one, this being the present coinage ratio of gold and silver. For example, six-

teen grains of silver equal one grain of gold, or four hundred grains of silver equal twenty-five grains of gold.

Below the spaces 9 and 10 and forming continuations thereof are produced supplemental spaces 13 and 14, in which are formed series 15 and 16 of apertures, aligned with and supplemental, respectively, to the series 7 and 8, and forming parts of the same columns of apertures 4, and opposite to the series 15 and 16 are printed series 17 and 18 of guide-numbers therefor. There are twelve apertures in the series 15, and there are twelve numbers in the series 17, reading "1, 2, 3," and so on down to "12." At the end of the series 15 is an additional aperture 15^a, and opposite it is a guide-number "17^a," reading "1." In the series 16 are eight apertures, and there are eight guide-numbers in the series 18, each reading "1^{1/2}."

Below the spaces 13 and 14 are formed apertures 19 and 20, having guide or index numbers 21 and 22, reading, respectively, "412^{1/2}" and "25^{8/15}," these being totals indicating the number of grains of silver and gold, respectively, in one dollar. At the foot of each of the two outer columns 4 and 4^a on the tablet is a "carry aperture" 23, having a guide or index number 24 reading "\$1.00," and at the foot of each space 14, between the apertures 20 and 23, is a series of apertures 25, five in number, unprovided with guide or index numbers and adapted to hold the pins or pegs used by each player.

35 The inner columns of apertures 4 and 4^a are formed in two parallel spaces 26 and 27, extending longitudinally of the tablet, in which spaces the apertures are arranged in two series 29 and 30, having corresponding guide-numbers or indexes 31 and 32. There are ten apertures in each series 29 and 30, and the ten guide-numbers in the corresponding series commence with "\$2" and increase by the successive addition of two dollars, so that 40 they read "\$2, \$4, \$6," and so on down to "\$20." At the foot of each of the inner columns of apertures 4 and 4^a is another aperture 33 to receive the pin or peg of the player winning the game. At the lower central part 45 of the tablet is a blank space 28, wherein may be printed an advertisement or other matter, and at opposite sides of this space 28 are letters "A" and "B" to indicate the sides selected by the players.

55 Each player is provided with six pins or pegs, one of these being colored black, as shown at 35 in Fig. 3, two being painted or colored to imitate gold and being used in the apertures 8, 16, 22, and 23, and three being 60 colored or painted to imitate silver and being used in the apertures 7, 15, 15^a, 19, and 23. The gold pins are indicated at 36 and 36^a in Fig. 3, the pin 36 being of greater length than the pin 36^a. The silver pins or pegs are indicated at 37, 37^a, and 37^b in Fig. 3, the pin 37 being of greater length than the pins 37^a and 37^b, and the pin 37^b having its head end

cut away or flattened at one side, and being used in the aperture 15^a, corresponding to one-half a grain of silver.

70 In playing the game forty-eight cards 6, such as are shown in Fig. 4, are employed, these cards being similar in size. Of the forty-eight cards four are "blanks," being unprovided with printed markings, as indicated at 38 in Fig. 4. The remaining forty-four cards are marked with numbers 34, printed at diagonally opposite corners and facing toward opposite ends, after the fashion of indexed playing-cards. Of these forty-four 80 printed cards, one is marked "4." There are six marked "1." Of those marked "2," "3," "4," "5," "6," "7," "8," and "9" there are two each. Five cards are marked "10." Of those marked "11," "12," "13," "14," 85 and "15" there are two each, and of those marked "16" there are six. The cards 6 are employed for determining the points made by the players, the tally-board and pegs or pins 5 being employed to record the points or keep 90 the score.

In playing the game, the cards 6 are shuffled and dealt, and by playing certain cards upon certain leads combinations are formed which may be counted. The points thus 95 made are of two kinds or classes, one class being scored by each player upon the column headed "Silver" and the other under the column headed "Gold." The object of each player is to make enough of these combinations to bring the pins or pegs 5 in each column down to the respective total-apertures 19 and 20. As soon as one pin has been placed in said aperture it is taken out and set in the carry-aperture 23 of its column, 100 counting in that position "\$1.00," and as soon as the other pin or peg 5 has been also brought down to its carry-aperture, so as to secure another "\$1.00," the player removes the pins from the carry-apertures 23 and 105 places his peg or pin 35 in the first aperture of, say, the series 29 on space 26, opposite the mark "\$2," signifying that he has won two points in the game. Thus it will be seen that not less than two points at a time can be 110 scored upon the central series 29 and 30 of apertures, the single points being tallied upon the apertures 23, at the lower end of the outer two columns.

115 The following regulations should be observed in playing the game: Two, four, six, or eight persons may contest the game, but since two cards constitute a "trick" two opponents must always play together, and when there are more than two players each two opponents will play together independent of the other players, although the partners will, of course, score together. If two persons are playing, twelve cards should be dealt, four at a time; if four are playing, twelve cards 125 should also be dealt; if six persons, eight cards, and if eight persons are playing, six cards should be dealt to each.

130 *How combinations are formed.*—Supposing

A deals and B leads, A, in order to take the trick, aims to play on B's card either a blank or one with a number which, added to the number of B's card, will make either "16" 5 or "1," unless A is playing to secure one grain or one-half grain of silver or one-tenth of a grain of gold. If the card played by A is one greater in its printed number than the card led by B, it enables A to count or score 10 one grain of gold in the aperture 8. If A plays a blank card or any card the number of which added to the number of B's card gives a sum of "16," this enables A to count sixteen grains of silver in the aperture 7. 15 By playing a card numbered "16" on a card numbered "1," or vice versa, one grain of silver may be scored. By playing the card numbered $\frac{1}{2}$ on a card numbered "16," or vice versa, one is enabled to count or score 20 the half grain of silver. By playing a card numbered "1" on one numbered "10," or vice versa, one is enabled to count or score one-tenth grain of gold. After single and fractional points have been once counted, 25 they cannot be again counted. After the player has scored sixteen grains of silver or one grain of gold twenty-five times he places the corresponding long pin 36 or 37 in the lower aperture 7 or 8, and proceeds with the 30 shorter pins to score in the supplemental series 15 and 16. When the series 15 has been traversed and the half grain of silver has been scored, the pin 37^b is placed in the aperture 15^a and the pin 37^a is placed in the carry-aperture 35. The half grain of silver may be scored at any time during the game. When the series 16 has been traversed, the player transfers his short pin 36^a to the carry-aperture 23. Having won two points, these are 40 then carried to the column 29 or 30.

A player playing a card the number of which corresponds with the number of the card on which it is played forfeits sixteen grains of silver or one grain of gold. 45 If desired the players may play but a part

of the game, the pins being placed opposite each other in the perforations 7 and 8. In this case the pins or pegs should be moved in a direction opposite to that in which they were before moved—that is, toward the top 50 of the tablet.

From the above description it will be seen that the improved game is of a very entertaining and instructive nature, and is of a very simple and inexpensive nature, and it 55 will be also seen that the game can be played with many variations and the apparatus employed may be somewhat modified without material departure from the principles and spirit of the invention, and for this reason I 60 do not wish to be understood as limiting myself to the precise form and arrangement of the parts herein set forth.

Having thus described my invention, I 65 claim—

A game apparatus comprising a tally-board or tablet having a set of apertures to receive the scoring pegs or pins of each player, each set comprising two parallel series having parallel series of guide-numbers corresponding in ratio, supplemental series of apertures also having guide-numbers, an additional aperture below one of said supplemental series, a carry-aperture at the end of each supplemental series, and another series 70 of apertures for recording points won, and having guide-numbers commencing with "2" and increasing by the successive addition of two, pins or pegs for each player comprising 75 a pin for each series of apertures and a separate pin for the additional aperture below the supplemental series of apertures, substantially as set forth.

In testimony that I claim the foregoing as my own I have hereto affixed my signature in 85 the presence of two witnesses.

SAMUEL CROCKER.

Witnesses:

JAMES M. HOUSEL,
FRANKLIN SPRINGER.
